thermatrol Corporation, Indianapolis, Ind., a corpora-
tion of Indiana

Filed Apr. 13, 1964, Ser. No. 79,661

Term of patent 3½ years

(Cl. D83—1)

Fig. 1.

Fig. 2.

Fig. 3.

FIG. 1 is a front perspective view of a control unit for regulating body temperature showing my new design.

FIG. 2 is a side elevation thereof.

FIG. 3 is a rear view thereof.

The dominant features of the design reside in the portions shown in full lines. The left side is substantially the same as the right side shown.

This application is a continuation-in-part of my prior application Serial No. D. 71,136, filed August 1, 1962.

I claim:

The ornamental design for control unit for regulating body temperature, as shown and described.
